UNITED STATES PATENT OFFICE

AUGUSTUS WILKES GUDGE, OF NEWARK, NEW JERSEY, AND EARL WENSLEY, OF CICERO, ILLINOIS, ASSIGNORS TO WESTERN ELECTRIC COMPANY, INCORPORATED, OF NEW YORK, N. Y., A CORPORATION OF NEW YORK

APPARATUS FOR PRODUCING ARTICLES FROM SHEET MATERIAL

Original application filed June 9, 1928, Serial No. 284,208. Divided and this application filed March 6, 1929. Serial No. 344,854.

This invention relates to an apparatus for producing articles from sheet material, and more particularly to an apparatus for forming damping rings for acoustic apparatus, and is a division of our Patent No. 1,759,844 of May 27, 1930.

The primary object of the present invention is to provide a simple and inexpensive apparatus for quickly and economically producing articles of sheet material.

In accordance with the general features of the invention, there is provided in one embodiment thereof, an apparatus for forming damping rings for acoustic apparatus in which a ribbon of paper of suitable width is first preliminarily folded in a longitudinal direction and then further folded in order to obtain a predetermined width in the longitudinal folds produced therein. After the ribbon is folded it is moved between a pair of guide rollers from which it passes between a plurality of spring pressed blades to a pair of pressure rolls which crease the folded paper to form a tape of predetermined width. The damping rings are then stamped from the tape by a die having a larger diameter than the tape thereby leaving an integral connection between the leaves of the damping ring.

It is believed that a complete understanding of the invention may be had by reference to the following description, taken in conjunction with the accompanying drawings, in which

Fig. 1 is a side elevation of the apparatus for forming damping rings embodying the features of the invention;

Fig. 2 is an enlarged view of a portion of the forming apparatus;

Fig. 3 is a fragmentary plan view of the apparatus taken on line 3-3 of Fig. 1;

Fig. 4 is a cross sectional view of a portion of the apparatus taken on line 4-4 of Fig. 1;

Fig. 5 is a detailed view taken on lines 5-5 of Fig. 1;

Fig. 6 is an elevation of a portion of the feeding mechanism with a section through a portion of the forming mechanism;

Fig. 7 is an end view of a portion of the

forming mechanism with a cross section through a portion of the advancing mechanism;

Fig. 8 is an elevation of a portion of the advancing mechanism taken on line 8-8 of Fig. 7;

Fig. 9 is a detailed view of a damping ring made by the improved forming apparatus, showing the leaves of the damping ring extended, and

Figs. 10 and 11 show a plan and end view, respectively, of the damping ring as it appears when completed by the apparatus with its composite parts in normal position.

Referring to the drawings, an apparatus embodying the invention is shown mounted upon a base 15. At one end of the base a roll of paper 16 is mounted upon an upright spindle 17 upon which it is resiliently held by a pair of springs 18 attached to the middle of the spindle. The spindle 17 is mounted in a cradle 20 pivoted at 19 permitting the edge of the roll to align itself with a vertical guide 21. The paper passes from the roll in the form of a ribbon around the guide 21 to a preliminary forming member 22 which is provided with an undulated slot (Fig. 5) whose undulations correspond to the number of folds to be imparted to the paper. From the preliminary forming device 22 the partially folded ribbon which has received its preliminary outline passes between a plurality of dovetailed blades 23 (Fig. 4) which are alternately supported on opposite sides of the ribbon. Each of the blades 23 is mounted in a tapering bar and the bars are supported upon standards 24 and 25 in such a manner that the blades converge in the direction of travel of the ribbon so that the ribbon enters the blades as it is formed by the preliminary forming device and leaves the blades in the form of a composite tape of six leaves.

The bars supporting the outside blades are carried by bolts which are movable in slots upon loosening of the thumb screws 26 to permit a separating of the blades for the purpose of threading the ribbon of paper through the blades when a new roll of paper is inserted in the apparatus.

It is quite important that the leaves of the

folded paper should have a predetermined width so as to leave a connection of uniform length between the leaves when a damping ring is later stamped therefrom. The width 5 of the leaves is determined by the amount of overlapping or dovetailing of the blades 23. In order to adjust the amount of overlapping of the blades, the standard 24 is mounted upon a slidable member 31, a portion of 10 which engages a T-shaped slot in the base. A clamping member 32 occupies the T-portion of the slot and serves to clamp the member 31 in place upon the operation of a cam 33 which exerts an upward force upon a bolt 15 34 to which the clamping member 32 is attached.

The folded ribbon passes from the blades 23 through a pair of guide rolls 35 to a plurality of parallel blades 36 which are alternately supported on opposite sides of the 20 ribbon. On the one side, the blades are carried by a support 37 and on the other side by an arm 38 which pivots about the point 39 (Fig. 3). The arm 38 also carries a pair 25 of compression members 41 (Fig. 7) which engage the blades 36 at the point where they contact with the folded ribbon and exert a pressure thereon. A spring 42 (Fig. 3) engages the arm 38 and serves to hold it in operative position. In order to thread the 30 paper tape through the blades 36 the arm 38 may be swung about its pivot 39 to render the blades more accessible. The folded paper passes from the blades 36 between 35 creasing rolls 43 and 44 and thence to a punch press 45 in which the damping rings 46 are stamped from the tape.

The roll 43 is mounted upon a shaft 49 and mounted upon the same shaft is a toothed 40 wheel 40 (Fig. 8) which is engaged by a plurality of pawls 47. The pawls 47 are mounted in a cup-shaped opening of a wheel 48 which is loosely mounted upon the shaft 49. A link 51 connects the wheel 48 to a bell 45 crank lever 52 which is actuated by an adjustable link 53 attached to a plunger 27 of the punch press 45, a movable punch and a stationary die carried by the plunger and the frame of the press being indicated at 28 50 and 29, respectively. The bell crank lever is provided with a slot 54 in which a slidable member 55 is adjustably mounted for the purpose of varying the amount of movement of the link 51 and the travel of the tape. 55 When the plunger 27 of the punch press 45 descends, the pawls 47 will slide over the toothed wheel 40, and when the plunger ascends, the pawls will engage the teeth on the wheel 40 to rotate the roll 43 an amount sufficient to advance an unstamped portion of the tape under the plunger of the press. A handle 50 is also provided by which the rolls may be rotated manually in threading a ribbon into the apparatus.

65 The rolls 43 and 44 are interconnected by

gears 56 and 57, causing the rolls to have the same peripheral speed. The lower roll is mounted upon an arm 58 which is pivoted at 59, permitting the roll to be dropped for the purpose of threading the paper tape through the rolls. The lower roll is maintained in pressing engagement with the upper roll and the paper tape by means of a spring pressed plunger 61 and may be disengaged therefrom by moving a cam shaped lever 62 to its vertical position.

In the operation of the apparatus, the paper ribbon passes over the guide 21 to the preliminary forming apparatus 22 where the ribbon is longitudinally formed into a plurality of undulations. The paper ribbon is then passed to the overlapping converging blades where folds of a predetermined width are imparted to the paper and from which the paper emerges in the form of an accordion pleated tape of a predetermined width passing through guide rollers 35 and between the spring pressed blades 36 into the rolls 43 and 44 where the edges of the tape are firmly pressed together to form a crease. The paper is then intermittently advanced to the punch press 45 by the mechanism described above. The diameter of the punch 28 is made slightly larger than the width of the folded leaves so that when a damping device 46 is stamped from the paper tape a narrow hinge 61 will remain on opposite sides of the damping device connecting the various leaves as shown in Fig. 9. It will be seen therefore that it is very important that the paper tape be 95 folded in such a manner that the leaves are always of a uniform width in order that the hinge or connection between the leaves shall have a uniform length. Figs. 9, 10 and 11 show a damping device in which the leaves are interconnected by hinges or connections 61 which form cords of the annular periphery of the damping device.

100 It will be understood that the embodiment of the invention herein described and illustrated is merely a convenient and useful form of the invention which is capable of many other modifications without departing from the spirit and scope of the invention.

105 What is claimed is:

1. In an article forming apparatus, means for supporting a ribbon of paper, a plurality of blades positioned to alternately engage opposite sides of the paper to produce folds, a guide roller for engaging the paper as it leaves the blades, a second set of blades for resiliently pressing the folded paper, and a pair of rolls for creasing the paper.
2. In an article forming apparatus, a spindle for rotatably supporting a roll of material, a cradle mounting for the spindle, a forming device, means for guiding the material to the forming device, a second forming device having overlapping blades engaging opposite sides of the material being

formed, and a pair of rolls for creasing the edges of the folded material.

3. In an apparatus for forming damping rings, means for producing a folded tape of a predetermined width including a set of blades for resiliently pressing the folded tape, a punch press having a punch for stamping rings from the tape, and means operatively connected to the punch for advancing the tape when the punch is withdrawn therefrom.

4. In an apparatus for forming damping rings, means for producing a folded tape of a predetermined width, a reciprocating punch for stamping rings from the tape, advancing means for the tape comprising a bell crank lever, an extensible link connecting the lever with the punch, and an adjustable connection between the link and the lever for adjusting the movement of the lever.

5. In an apparatus for producing damping rings, a preliminary forming means for producing a plurality of longitudinal undulations in a ribbon of paper, means for converging the undulations to form a tape, a pair of rollers for guiding the tape as it leaves the converging means, a pair of creasing rolls, a plurality of parallel blades between which the tape is guided and pressed before being acted upon by the creasing rolls, and means for stamping damping rings having interconnected leaves from the tape.

6. In an apparatus for producing damping rings, means for longitudinally folding a ribbon of material, a pair of creasing rolls, a plurality of parallel blades between which the folded ribbon is guided and pressed before being acted upon by the creasing rolls, resiliently mounted arms for exerting a pressure on the blades, and means for stamping damping rings from the folded ribbon.

7. In an apparatus for producing damping rings, means for folding a ribbon of material into a tape of predetermined width, a punch having a diameter greater than the width of the tape, and means for actuating the punch to stamp damping rings having interconnected leaves from the tape.

8. In an article forming apparatus, means for supporting a ribbon of material, means for producing open folds therein of a predetermined width, means for closing the folds in the ribbon and creasing the edges thereof, and a plurality of parallel spring pressed blades between which the ribbon is guided and pressed before being acted upon by the fold closing and edge creasing means.

In witness whereof, we hereunto subscribe our names this 19th day of February, A. D., 1929, and this 22d day of February, A. D., 1929.

AUGUSTUS WILKES GUDGE.
EARL WENSLEY.
